Japanese Notification dated Feb. 25, 2016, for Japanese Application No. 2015-018433 with the partial English translation.

Primary Examiner — Holly E Thurman*(74) Attorney, Agent, or Firm* — Birch, Stewart, Kolasch & Birch, LLP(57) **CLAIM**

The ornamental design for an aperture adjusting device, as shown and described.

DESCRIPTION

FIG. 1 is a perspective view of an aperture adjusting device showing our new design;

FIG. 2 is a front view thereof, the rear view is identical image;

FIG. 3 is a top plan view thereof, the bottom plan view is identical image;

FIG. 4 is a right side view thereof, the left side view is identical image;

FIG. 5 is a perspective view of the aperture adjusting device showing a state in which the shield area is maximum;

FIG. 6 is a front view of the aperture adjusting device showing a state in which the shield area is maximum;

FIG. 7 is a front view showing changing state of the shield area between the state of FIG. 2 and the state of FIG. 6; and,

FIG. 8 is a front view showing changing state of the shield area between the state of FIG. 2 and the state of FIG. 6.

1 Claim, 4 Drawing Sheets(56)
